UNITED STATES PATENT OFFICE.

ADAM F. LAMB, OF NEW YORK, N. Y.

DIRECTION INDICATOR.

1,402,623.

Specification of Letters Patent. Patented Jan. 3, 1922.

Application filed February 19, 1921. Serial No. 446,409.

To all whom it may concern:

Be it known that I, ADAM F. LAMB, a citizen of the United States, and a resident of the city of New York, Rockaway Beach, 5 borough of Queens, in the county of Queens and State of New York, have invented a new and Improved Direction Indicator, of which the following is a full, clear, and exact description.

10 This invention relates generally to the class of signalling devices and has particular reference to a direction indicator adapted to be associated with a motor vehicle for the purpose of signalling the intention of the 15 operator to make a turn, or bring his vehicle to a stop.

The invention contemplates the provision of a direction indicator for motor vehicles which will effectively indicate the intention 20 of the driver to turn or stop oncoming or following traffic.

One of the principal objects of the invention is to provide a simple, inexpensive, and a compact indicator which is applicable 25 to any standard form of vehicle now in use and one which is located within convenient reach of the operator and readily operable by him.

A further object of the invention resides 30 in the combination with an indicator of the character set forth, of illuminating means therefor which is automatically actuated when the device is shifted to indicating position.

35 With the above recited and other objects in view, some of which appear hereafter, reference is had to the following specification, the appended claims and the accompanying drawings, in which—

40 Figure 1 is a side elevation of the indicator, parts being in section to disclose the underlying structure.

Figure 2 is a sectional plan view thereof taken approximately on the line 2—2 of 45 Figure 1.

Referring to the drawings by characters of reference, 10 designates a casing or housing which is adapted to be secured to the side of a vehicle adjacent the driver's seat. The 50 casing is open at its outer side and provided with inwardly projecting, rearwardly inclined flanges 11, the inner free ends of which are spaced apart to provide a vertical opening 12. A pair of standards 13 are 55 secured within the casing adjacent its inner side to constitute a supporting frame for

the inner end of a lazy-tong 14 consisting of a plurality of pivotally connected cross bars 15. The lower pivot 16 of the inner set of bars 15 is passed through the standards 13 and the upper pivot 17 thereof is passed through the vertical slots 18. The extremities of the innermost bars 15 extend through a vertical slot 19 in the inner wall of the casing and one of the said bars is 60 provided with a manipulating handle 20. By this arrangement, upon depressing the handle 20, the lazy-tong will be projected through the opening 12 of the casing and by lifting the handle the same will be retracted within the casing. The outer free extremity of the lazy-tong is operatively connected to a head 21 which serves to close the space or opening 12 between the flanges 11 when the lazy-tong is retracted. A pair 70 of vertical rollers 22 are journaled in the upper and lower walls of the casing, and a pair of flexible strips of canvas or any other suitable material 23 are connected at one end to the rollers and at the opposite end 75 to the head 21. Helical springs 24 are suitably connected at one end to each roller and at their opposite ends to the casing, the same serving to normally tension the roller to effect the winding of the strips 23 thereon. When the lazy-tong is projected or extended, the strips are adapted to be unwound from the rollers and the spring is placed under tension. As the lazy-tong is 80 retracted, the springs will operate to wind 85 the strips on the rollers. The outer surfaces of each strip are suitably inscribed with a hand 25 or other indicia indicative of the invention of the driver to make a turn or stop. In order to provide means which 90 will render the device visible at night, electric lamps 26 are mounted in the flanges 11 and suitably included in a circuit having a source of electrical energy. A pair of 95 binding posts 27 and 28 are connected to opposite terminals of the circuit, the binding post 27 having a contact member 29 secured thereto. The binding post 28 is provided with a spring tongue 30 which is normally disposed out of contact with the member 29. 100 A roller 31 is mounted on the pivot 17 for the purpose of effecting the contact of the spring tongue with the member 29 when the lazy-tong is extended. By this arrangement, it will be obvious that upon projection 110 of the indicating element from the casing, the circuit will be closed to energize the

lamps 26 and illuminate the outer surfaces of the strips 23. When the device is in non-indicating position, the head 21 will close the opening to render the same water and dust proof.

While there has been illustrated a preferred embodiment of the invention, it is to be understood that variations and modifications falling within the scope of the appended claims may be resorted to when found expedient.

I claim:

1. A direction indicator for vehicles comprising a casing adapted to be secured to the side of a vehicle having inwardly projecting inclined outer end walls separated at their inner ends to provide a slot, an extensible arm secured at its inner end within the casing and projectable through said slot, a pair of spring rollers journaled at opposite sides of the secured end of said arm within the casing, strips having traffic signaling indicia secured to each roller at one end and normally wound thereon, said strips being secured at their other ends to the opposite sides of the free end of the arm, a head secured to the free end of the arm, means projecting through the inner wall of the casing for effecting the contraction and extension of the arm, said head serving upon retraction of the arm to close the slot, an illuminating de-

vice on the inclined walls for flooding the outer surfaces of the strips with light, and automatic means operable upon projection of the arm for actuating the illuminating means, the outer surface of said inclined walls serving as a reflecting means for illuminating the same.

2. A direction indicator for vehicles, comprising a hollow casing adapted to be secured to the side of a vehicle having inwardly projecting inclined walls, spaced apart at their inner ends to provide a slot at the side of the casing, a lazy tong arm secured within the casing and projectable through the slot, a head at its outer end serving upon retraction of the arm within the casing to engage with the inwardly projecting walls to close the slot, a pair of spring rollers journaled in the upper and lower walls of the casing, strips secured at their inner ends of the arm and at their outer ends to the opposite sides of the free end of the arm, said strips bearing traffic signaling indicia thereon and serving to normally place the rollers under tension upon projection of the arm, and means projecting through the inner wall of the casing for actuating the arm to effect its projection through the slot.

ADAM F. LAMB.
